[57] CLAIM

The ornamental design for a game board, as shown and described.

DESCRIPTION

FIG. 1 is a top plan view of a game board, showing our new design;

FIG. 2 is a rear left side elevational view, the other side being identical;

FIG. 3 is a bottom plan view thereof;

FIG. 4 is a rear right side elevational view thereof, the other side being identical;

FIG. 5 is a top plan view of the second embodiment;

FIG. 6 is a front elevational view of FIG. 5;

FIG. 7 is a right side elevational view of FIG. 5;

FIG. 8 is a bottom plan view of FIG. 5;

FIG. 9 is a rear elevational view of FIG. 5;

FIG. 10 is a left side elevational view of FIG. 5;

FIG. 11 is a top plan view of a third embodiment;

FIG. 12 is a front elevational view of FIG. 11;

FIG. 13 is a right side elevational view of FIG. 11;

FIG. 14 is a bottom plan view of FIG. 11;

FIG. 15 is a rear elevational view of FIG. 11;

FIG. 16 is a left side elevational view of FIG. 11.
